UNITED STATES PATENT OFFICE.

JOHN A. TIEFERT, OF MIAMI, FLORIDA.

DISPLAY REFRIGERATOR.

1,402,119.

Specification of Letters Patent. Patented Jan. 3, 1922.

Application filed June 18, 1921. Serial No. 478,735.

To all whom it may concern:

Be it known that I, JOHN A. TIEFERT, a citizen of the United States of America, residing at Miami, in the county of Dade 5 and State of Florida, have invented certain new and useful Improvements in Display Refrigerators; and I do hereby declare that the following is a full, clear, and exact description of the invention, such as will enable others skilled in the art to which it 10 pertains to make and use the same.

This invention has reference to improvements in refrigerators and has for an object to provide a refrigerator of the display 15 or show-case type wherein air is cooled by a refrigerating medium and caused to circulate to all parts of the case, thus maintaining the interior of the same at an even or uniform low temperature.

It is also an object of the invention to provide novel means for circulating the cooled air within the case from the refrigerating medium in such a manner as to cause the removal of the warmer air at the top of the 25 case downwardly and directly over-said medium for recooling, and to prevent any material variance in the interior temperature of the case, hence, insuring the functioning of the same at its maximum efficiency 30 throughout the period of use thereof.

Yet another object of the invention is to provide a display refrigerator having the top and door thereof so constructed and mounted as to permit of the escape of the 35 warmer air only with opening of said door, and likewise, in the event of leakage by the door and its frame, to permit only the escape of the warmer air.

Other objects will be in part obvious and 40 in part pointed out hereinafter.

In order that the invention and its mode of operation may be readily understood by persons skilled in the art, I have in the accompanying illustrative drawings and in the 5 detailed following description based thereon, set out one embodiment of the same.

In these drawings:

Figure 1 is a perspective view of the improved refrigerator; 45 Figure 2 is a horizontal section therethrough; and,

Figure 3 is a fragmentary transversal section through the same.

Having more particular reference to the 50 drawings, in connection with which like characters of reference will designate cor-

responding parts throughout, my improved display refrigerator consists of a case or housing indicated in its entirety by the numeral 1, the top, side, and one of the end walls thereof being formed of glass, whereby they will be transparent for purposes of display. In this connection, it is to be noted that in constructing the transparent walls of the housing, I employ a three layer or ply 60 arrangement of glass, spacing each of the plies thereof sufficiently to provide heat insulating or dead air space as between them and by consequence, affording means for preventing condensation upon said transparent 65 walls with the resultant interference with display of the contents of the case, as well as providing the same with a positive means for insulating the interior of the case from the outer atmosphere, which, of course, is at 70 75 a higher temperature.

The top wall 2 of the case or housing is inclined upwardly towards the rear wall of the same as clearly shown in the Figure 3 whereby the warmer air within the case 80 will be caused to move towards the rear of the same at all times.

To permit of access to the interior of the refrigerator, a door 3 is horizontally hinged as at 4 to the rear wall and, as will 85 be understood, is adapted to be snugly received within a suitable frame or way provided therefor, the mounting of said door being such as to cause vertical movement of the same when swung to its open position 90 and also, by being hinged at its bottom, will cause the vertically swinging door to open downwardly, hence, first opening the refrigerator adjacent its top wall 2 with downward swinging of the door. With the resultant opening of the upper portion of the refrigerator first, it is to be understood that the warmer air found at the top of the 95 refrigerator interior will be completely exhausted.

A suitable form of catch or lock 5 may be and preferably is provided the free portion of the door in order that the same may be releasably held in its closed position.

Arranged upon the solid bottom of the 105 refrigerator 1 at a point adjacent the rear wall thereof is a refrigerating coil 6 the terminals of which are extended from one end wall of the refrigerator in order that they may be connected with a suitable 110 circulating and refrigerating means, such ends, if desired, being screw-threaded as at 7 for

an obvious purpose. A flat shield or board 8 is arranged over the refrigerator coil and, obviously, serves to prevent direct contact of the goods to be preserved within the case 5 therewith, this shield being arranged longitudinally of the case and having its opposite ends connected in a suitable manner to the frames of the opposite end walls of the refrigerator receiving the glass or other 10 transparent walls hereinbefore described. The rear marginal portion of the shield is extended flush with the way for receiving the door 3 in the rear wall of the refrigerator and by consequence, affords a closed 15 pocket therefor which will prevent the escape of cooled air directly from the coil with opening of the door to its full downward position.

As means for creating a forced circulation 20 of air within the refrigerator and to insure direct contact of the warmer air with the coils during such circulation, spaced vertical air ways are arranged adjacent the inner side of the rear wall and upon the opposite sides of the downwardly swinging door 25 3, such circulating ways being formed by constructing hoods 9 consisting of tightly joined strips of material having their inner ends resting upon the rear portion of the 30 longitudinal shield 8 and the adjacent portions of said shield cut away as at 10, whereby to establish uninterrupted communication as between the top of the inclined wall 2 and the coil 6 arranged on the bottom of 35 the refrigerator. Due to the provision of these several air circulating ways at the rear of the refrigerator, it will be understood that a thermosyphonic circulation of air will occur within the refrigerator housing 40 and by consequence, will serve to maintain the interior temperature of the same at its minimum. Thus, by reason of the constant circulation of the cooled air interiorly of the refrigerator, I am enabled to maintain the 45 same at a most efficient low uniform temperature. Furthermore, as previously stated, due to the fact that the door 3 opens downwardly, first exposing the upper portion of the interior of the refrigerator, the warmer 50 air found at the top thereof will be first exhausted and therefore, the desirable low temperature of the refrigerator interior with opening of the same will not be materially detracted from, but as stated, such 55 opening will serve to thoroughly scavenge the interior of the refrigerator of the

warmer and impure air, thereby lending to its efficiency and also to its sanitary conditions.

While I have not hereinbefore laid any particular stress upon the detailed construction of the refrigerator housing, it is, of course, to be understood that the same may be made of various sizes or designs and, furthermore, that the arrangement of the 65 vertically swinging door 3 and its frame therefor is such as to provide the nearest possible approach to a fluid tight connection, such an arrangement being old and well known in the art. Also, if found to be desirable, the size or specific formation of the 70 refrigerating coil 6 may be changed or varied, such as conditions or preference may dictate.

Manifestly, the construction shown is 75 capable of considerable modification and such modification as is within the scope of my claims, I consider within the spirit of my invention.

I claim:

1. A refrigerator comprising a housing, refrigerating means arranged in the bottom of the housing, a shield extending over the refrigerating means, and a plurality of vertical air circulating ways formed adjacent 80 the rear wall of the housing communicating with the top and bottom portions of said housing.

2. A refrigerator comprising a housing, the top wall of which is inclined upwardly 90 towards its rear wall, refrigerating means on the bottom of the housing, a longitudinal shield extending over said refrigerating means and forming a rearwardly closed pocket therefor, and a plurality of vertical 95 air circulating ways formed adjacent said rear wall communicating with the top and bottom portions of the housing.

3. A refrigerator, comprising a housing, the top wall of which is inclined upwardly 100 towards its rear wall, refrigerating means on the bottom of the housing, a longitudinal shield extending over said refrigerating means and forming a rearwardly closed pocket therefor, a plurality of air circulat- 105 ings ways within the refrigerator adjacent its rear wall and communicating with the top and bottom portions of the same, and a downwardly opening door in said rear wall.

In witness whereof I have hereunto set 110 my hand.

JOHN A. TIEFERT.
